UNITED STATES PATENT OFFICE.

SVEN WILLIAM N:SON WIHLJAM, OF MALMO, SWEDEN.

MAP-DISPLAY DEVICE.

Application filed January 4, 1926, Serial No. 79,232, and in Sweden October 14, 1925.

This invention relates to a map-display device of the type in which the map extends between a pair of rollers arranged parallel to each other in spaced relationship, the 5 map being wound round said rollers so that it may be unwound from the one roller and simultaneously wound upon the other roller, or vice versa, in order to adjust that visible portion of the map displayed between the 10 rollers.

The object of the invention is to produce a map-display device of the above type in which the map even if of considerable length, always runs correctly and with just 15 the right amount of friction round the rollers and does not tend to wind up crookedly or to become jammed or displaced or even torn. Further the map-display device is constructed in such a manner that it will be 20 most suitable and convenient for military personnel, tourists and motorists who have to be equipped with maps covering large districts and for whom it is important to be able to locate their position correctly on 25 the map in all weathers and also in darkness.

The invention is illustrated by way of example, in the accompanying drawing, in which:—

30 Figure 1 shows a longitudinal section through the map-display device according to the invention.

Figure 2 is a top plan view of the same with the casing in section.

35 Figure 3 shows a transversal section of the device.

The framework of the device, preferably 40 constructed of wood, but also adapted for instance, to be cast or pressed in one piece of aluminium, papier-mâché or other suitable material, consists of a pair of end walls 1 and a pair of side members 2 connecting the latter. Somewhat outside of the side members 2 and journaled in the end walls 45 1 are two rollers 3, preferably of wood, the ends of the map being attached thereto in the manner to be more fully described in the following.

The map, designated as 4 and shown with 50 dash-dotted lines in Fig. 3 may be unwound from the one roller and simultaneously wound up upon the other roller, or vice versa, by rotating the rollers 3 by means of knobs 5 fixed to the ends of the rollers 55 projecting through the foremost end wall 1. In order to prevent the map, when it is be-

ing unwound or wound up, from tending to run crookedly which may cause crumpling or tearing or jamming at the end walls, the map rollers 3 are thickest at their 60 centres and diminish conically towards both ends. By means of this arrangement the map will always have the tendency, when it is wound up, to right itself on the centre of the roller, and this has proved to be of the 65 utmost practical importance. This effect is further assisted by having the end portion 4^a of the map pointed, so that the fastening of the end of the map to the roller is also 70 facilitated in that it will be quite sufficient for this purpose to thread the pointed end of the map through a longitudinal slit 4^b in the roller, although of course other fixing means may be employed. The end portion 4^a itself may preferably consist of thin cloth 75 or the like which is gummed onto the edge of the map, which latter is generally made exclusively of paper.

From the rollers the map is led over the side members 2 which for this purpose are 80 formed as guides. Previously, similar guides, for example in the form of guide rollers, have been employed in devices of similar kind, but they have been placed in such a manner that the map has been bent 85 at approximately a right angle or at an acute angle over the guide members. As shown on the drawing the guide members according to the present invention are placed inwardly of their rollers 3, or in other words 90 they are arranged between the rollers in such a manner that the map is bent over the guide member at a very obtuse angle. This arrangement in combination with the double-conical map rollers has proved to 95 add materially in obtaining an easy and better guiding and running of the map and in reducing the stresses exerted on the latter. The same result is further obtained by forming the upper edge 2^a of the side members 100 2, upon which the map glides, of slightly arcuate form so that it is highest at the centre portion and diminishes in height towards the ends, as clearly disclosed in Fig. 1. In cross section the upper edge of the 105 side members is rounded off, and their inner sides 2^b facing each other are preferably convex, as illustrated in Fig. 3.

The map rollers 3 at their ends projecting from the end wall 1 are provided with 110 grooved pulleys 7, preferably arranged on the operating knobs 5, and similarly grooved

5 pulleys 8 are journaled on studs on the end wall at a short distance inwardly of the knobs 5. Over each of the pairs of pulleys 7 and 8 is arranged an endless band, preferably in the form of a slightly tensioned rubber ring 9. These rings have proved to form a very effective elastic brake for the map rollers, so that these rollers maintain their set position and always tend to keep 10 the map stretched.

15 Between the lower edges of the side members 2 is fastened a plate 10 having a polished surface. This plate together with the convex sides 2^b of the side members 2 forms a suitable light reflector underneath the portion of the map 4 extending from one side member to the other. One corner of this plate 10 is cut and bent as at 11 to form a housing for receiving a dry battery for 20 pocket lamps, said battery being inserted from the front end wall and kept in position by means of a flat spring 13 fixed to the underneath side of the plate 10. The housing thus formed has further a part 14 bent 25 downwardly against which part one contact piece 15 of the battery 12 abuts. The front end wall 1 is provided with an insulated screw 16 which is adapted to be screwed against the other contact piece 17 of the 30 battery 12 in order to close a circuit containing a couple of incandescent lamps 18 and 19. These lamps are mounted in suitable holders fixed to the inner sides of the end walls near the two side members 2. The 35 lamps together with the reflector 10 serve to illuminate from underneath the portion of the map between the side members for facilitating the reading of the map during darkness.

40 The whole frame together with all the above described elements mounted thereon is inserted in a casing 20, preferably of leather, and is adapted to be withdrawn therefrom. For this purpose the casing is provided at its 45 front portion with an opening which is closed by means of a flap 21 having slits for the operating knobs 5 and being further provided with buttons 22 or the like for buttoning the same to the underneath side of the 50 casing. The upper side of the leather casing is provided with an opening which is closed by means of a transparent sheet 23 of celluloid or the like through which the displayed portion of the map is made visible and may 55 be studied. The whole apparatus is adapted to be carried by a thong over the shoulder in a similar manner as with known map cases. One end of the thong (not shown in the drawing) may be fastened by hook and eye 60 to the leather encasement.

65 It is to be noted that the apparatus in the form described above may receive a map of several yards length, and for all practical purposes the map may be wound up and unwound on the map rollers as much as desired

without the map becoming damaged or jammed or in any way displaced. The map-display device, therefore, may receive maps covering a whole country in a scale generally adopted for use by motorists or military personnel. For example, the map-display device according to the invention having overall dimensions 10 $\frac{1}{4}$ "x8 $\frac{1}{4}$ "x15 $\frac{1}{8}$ " may contain all the road maps for the whole of Great Britain, Scotland and Ireland. In 75 order to accomplish this the map may be divided up and composed of sheets or sections arranged to follow each other in such a manner that when the left operating knob, for instance, is turned anti-clockwise, the 80 map will glide from the west to the east and after the extreme east part has been reached to the next section north of the extreme west section just left, and vice versa when the right operating knob is turned 85 clockwise. To find the desired connection on the next section, main roads or the like are specially marked at the point where it terminates at the edge of a section, and a like mark is set out on the corresponding next 90 section or the section above or below at the edge, where the same main road or the like commences. These marks may consist of conspicuous red letters. In using the map-display device and when for instance a main road or railway line or the like terminates at the edge of the displayed section, it is only necessary to observe the mark set out at this edge and then shift the sections until the same mark appears on the edge opposite to that which one has left, which method ensures that the continuation of the main road or the like is correctly displayed. This 95 prompting means has proved to be of the greatest practical importance.

100 Although the subject of the invention has above been described in detail with respect to a certain embodiment forming the result of experiments, it is to be understood that the invention is not limited to the details or 110 elements shown and described, but they may be varied in various respects without affecting the scope of the invention.

115 What I claim and desire to secure by Letters Patent is:—

1. A map-display device comprising a frame including two end walls and two side members, double-conical map rollers journaled in the end walls outside of the side members, the side members being rounded off at the upper edge upon which the map is to glide and the upper edge in a longitudinal direction being arcuate so that it is highest at its middle portion and diminishes in height towards the ends.

120 2. A map-display device comprising a frame including two end walls and two side members having rounded off and arcuated upper edges, double-conical map rollers journaled in the end walls outside of the 130

side members and each provided with a longitudinal slit for inserting pointed ends of a map therein, polished plate means fixed to the under side of the side members, the 5 inner sides of the side members facing each other being convex.

3. A map-display device comprising a frame including two end walls and two side members, double-conical map rollers journaled in the end walls outside of the side members, a polished plate fixed to the under side of the side members, a pair of incandescent lamps arranged on the inner sides of the end walls inwardly of and near the 15 side members, a corner of the polished plate being cut and bent to form a housing for a dry battery arranged to supply current to the lamps.

4. A map-display device comprising a frame including two end walls and two arcuate side members having convex inner sides, two double-conical map rollers journaled in the end walls outside of the side members, a polished plate fixed to the under 25 side of the side members, illuminating means including operating means for the same arranged within the space between the end walls and the side members, the ends of the rollers protruding through the front end wall and being provided with operating 30 knobs and grooved pulleys, similar grooved pulleys journaled on studs on the front end wall, the grooves in said grooved pulleys being arranged to receive in pairs an endless band in the form of slightly tensioned rubber 35 rings.

5. A map-display device comprising a frame including two end walls and two side members having rounded off and arcuated

upper edges, map rollers journaled in the 40 end walls outside of the side members and each provided with fastening means for a map, polished plate means fixed to the under side of the side members, the inner sides of the side members facing each other being 45 convex.

6. A map-display device comprising a frame including two end walls and two side members, map rollers journaled in the end walls outside of the side members, a polished 50 plate fixed to the under side of the side members, a pair of incandescent lamps arranged on the inner sides of the end walls inwardly of and near the side members, a corner of the polished plate being cut and bent to form a 55 housing for a dry battery arranged to supply current to the lamps.

7. A map-display device comprising a frame including two end walls and two arcuate side members having convex inner 60 sides, two map rollers journaled in the end walls outside of the side members, a polished plate fixed to the under side of the side members, illuminating means including operating means for the same arranged within 65 the space between the end walls and the side members, the ends of the rollers protruding through the front end wall and being provided with operating knobs and grooved 70 pulleys, similar grooved pulleys journaled on studs on the front end wall, the grooves in said grooved pulleys being arranged to receive in pairs an endless band in the form of slightly tensioned rubber rings.

In testimony whereof I have signed my 75 name to this specification.

SVEN WILLIAM N:SON WIHLJAM.
